(57) **CLAIM**

The ornamental design for a gear and axle combination, as shown and described.

DESCRIPTION

FIG. 1 is a perspective view of the gear and axle combination showing my new design;

FIG. 2 is a front view thereof;

FIG. 3 is a rear view thereof;

FIG. 4 is a right side view thereof;

FIG. 5 is a left side view thereof;

FIG. 6 is a top plan view thereof;

FIG. 7 is a bottom plan view thereof;

FIG. 8 is an exploded view of the gear and axle combination design shown in FIG. 1;

FIG. 9 is a perspective view of the gear and axle combination showing my new design in a second embodiment;

FIG. 10 is a front view thereof;

FIG. 11 is a rear view thereof;

FIG. 12 is a right side view thereof;

FIG. 13 is a left side view thereof;

FIG. 14 is a top plan view thereof;

FIG. 15 is a bottom plan view thereof; and,

FIG. 16 is an exploded view of the gear and axle combination design shown in FIG. 9.
